UNITED STATES PATENT OFFICE.

FRANK A. HALLECK, OF OAK PARK, ILLINOIS, ASSIGNOR TO SULLIVAN MACHINERY COMPANY, A CORPORATION OF MASSACHUSETTS.

FORGING MACHINE.

Application filed July 11, 1917. Serial No. 179,952.

To all whom it may concern:

Be it known that I, FRANK A. HALLECK, a citizen of the United States, residing at Oak Park, in the county of Cook and State of Illinois, have invented certain new and useful Improvements in Forging Machines, of which the following is a full, clear, and exact specification.

My invention relates to forging machines. 10 It has for its object to gage drill steels or the like in an improved manner whereby a wide variation in gage may be obtained. A further object of my invention is to provide improved and simplified gaging mechanism of rugged character whereby the necessity for utilizing loose pieces in the dies is eliminated and whereby, by a relatively simple adjustment adapted to be made by even an unskilled operator, the desired 20 variation in gage may be effected. A still further object of my invention is to provide improved means for simultaneously accurately gaging and forming reaming edges on the wings of drill bits. These and other 25 objects of my improvement, will, however, hereinafter more fully appear.

In the accompanying drawings, I have shown, for purposes of illustration, one embodiment which my invention may assume in practice, it being understood, however, that the invention may be used in other relations.

In these drawings,—

Fig. 1 is an end elevation of a drill sharpener equipped with my improvement.

Fig. 2 is an enlarged rear end elevation of the swaging dies equipped with my improved gaging mechanism.

Fig. 3 is a vertical sectional view taken on line 3—3 of Fig. 2, showing in dotted lines the position of a bit to be gaged.

Fig. 4 is a vertical sectional view taken on line 4—4 of Fig. 2.

Fig. 5 is a side elevation of the dies shown in Fig. 2.

Fig. 6 is a plan view of the die mechanism shown in Fig. 2, the upper die being removed to facilitate illustration.

Fig. 7 is an enlarged perspective view 50 of the gage key.

Fig. 8 is an enlarged perspective view of the gage plate.

Fig. 9 is a perspective view of the gage key showing the lower gaging die.

Fig. 10 is a transverse section on the line 55 10—10 of Fig. 9.

Fig. 11 is a fragmentary view on an enlarged scale of the upper gaging die, showing the relative curvatures of the gaging surface of the upper die as compared with 60 the maximum and minimum gages to be imparted thereby.

In this illustrative construction, I have shown my invention as applied to use in gaging "cross" bits made or sharpened on 65 a sharpener of standard construction. As shown, this sharpener comprises a suitable base 1 carrying thereon the usual clamping and upsetting mechanisms (not shown), and a lower swaging die 2 adapted to cooperate with a movable upper swaging die block 3, the latter being reciprocated by a suitable motor 4 and controlled through valve operating mechanism 5 by means of operative connections 6 controlled by a foot 70 lever 7.

In the construction illustrated, the swaging dies 2 and 3 carry the gaging mechanism and are each provided with the usual swaging apertures 8 and 9 therein adapted to 80 swage the bit to substantially the form desired, these apertures for purposes of illustration herein being shown as those adapted to bring the bit to the form of a "cross" bit, although obviously apertures adapted 85 to produce other forms of bits may be used if desired. As shown, these cooperating apertures 8 and 9 on the different dies are preferably disposed at one side of the center line of the die blocks 2 and 3 and longitudinally thereof so that an operator standing in front of the machine may readily insert the steel between the same and withdraw the steel therefrom, and my improved gaging dies are preferably, though not 90 necessarily, disposed on the opposite side of the center line of the die blocks and relatively close to the apertures 8 and 9 so that the drill steel may be readily shifted from one set of dies to the other. If desired, 100 suitable working surfaces, herein flattening surfaces 10, may be provided between the two sets of dies so that these surfaces may be available for ordinary steam hammer purposes. It will be noted that I have 105 vented the sides of my swaging dies as at 9' to permit the escape of scale.

In the form of my improvement shown

herein, the upper die 3 is provided with a longitudinally disposed gaging groove 11 having a tapered bottom 12 disposed substantially at an angle of five degrees to the horizontal and extending from one end of the block to the other, a suitable laterally disposed slot or groove 13 being provided to receive one of the laterally disposed wings on the bit when the vertically disposed wings of the "cross" bit are engaging with the surface 12. It will be noted from Figs. 2, 3 and 11 that the curvature of the surface 12 at the rear end of the same, that is, the end adapted to gage bits of maximum gage, is substantially flatter than the curvature of the same at the front end of the die, that is, the end adjacent which bits of minimum gage are operated on, and that the surface joining these curvatures is flatter at any point than an arc of a circle corresponding to the gage of a bit to be gaged at that point. In Fig. 11 there is approximately shown the relative curvature of the opposite ends of the surface 12, as compared with the curvatures of bits of the maximum and minimum gages to be treated. Thus, it will be seen that a surface 12 is produced which is adapted to cooperate with a cooperating gaging surface of fixed curvature carried on the lower die, hereinafter described, and is also adapted to form reaming edges on bits of varying gage as the same are gaged. Cooperating with the gaging die thus formed on the upper swaging die 3, is the gaging mechanism carried by the lower die. As shown, this die is provided with a longitudinally disposed grooved or cut-away portion 14 disposed immediately beneath the groove 11 in the upper die 3 and having an inclined bottom surface 15 preferably disposed in a single plane and at an angle to the horizontal of ten degrees, or twice as many degrees as the inclination of the surface 12. Disposed in this groove 14, is a gaging key or die 16 having a lower inclined surface adapted to engage with and slide over the surface 15, and disposed at the same angle as the latter, and an upper surface 17 disposed substantially in a horizontal plane. As shown, this key is also provided with an upstanding abutment 18 at its rear end and on its upper surface, adapted to be engaged by the cutting edge of the steel and herein provided with a central notch having tapered laterally diverging sides 19, the upper surfaces of the notch walls also preferably being sloped away as shown at 20. As illustrated, the space in front of the notch is also cut away as shown at 21, preferably at an angle corresponding to the angle of the surface 12 in such a manner as to receive the portion of the bit adjacent the cutting edge thereof. The curvature of the surface 21 bears such a relation to that of the surface 12, the same herein

for example being a mean of the latter surface, that a surface gaged exactly to the desired shape by the surface 12 will not be materially altered in shape when turned so as to rest upon the surface 21 while the opposite wing is being gaged. It will therefore be obvious that two wings of a cross bit will be substantially perfectly formed and that the others will deviate only in the minutest manner from perfect contour and well within commercial limits. From the foregoing it will be clear that a bit inserted over the surface 17 with its end in position against the abutment 18, will be acted upon by the two surfaces 21 and 12 in such a manner as to gage the same and produce a five-degree taper on the wings thereof as far back as the surface 21 is extended.

In my improved construction, the gage key 16 is preferably adjustable longitudinally of the surface 15 on the lower swaging die 2 so that various gages may be readily obtained, the key being slideable along the surface 15 and the adjacent wall of an outer confining member, herein shown in the form of a vertically disposed gage plate 22 suitably clamped to the lower die 2 by means of bolts 23 in such a manner as to confine the key 16 against vibration and yet permit a longitudinal movement of the latter. Obviously, with such a construction it is only necessary to slide the gage key longitudinally of the die 2 to vary the gage obtainable as desired and at the same time, due to the provision of the cooperating surfaces 21 and 12, to produce the desired taper on the working end of the bit regardless of the position of the gage key relative to the upper surface 12. While various other means may be used to maintain the gage key 16 in position, I have herein provided improved means whereby the same may be definitely locked in a wide range of different positions and adjusted with great facility. These means, as shown, include an adjustable rigid connection between the gage key 16 and the gage plate 22, and include a downwardly extending tail portion 24 formed on the gage key and provided with a series of aligned apertures 25 therein and a tail portion 26 on the gage plate provided with a plurality of series of aligned apertures 27, 28, 29, and 30, the apertures in each series being disposed in staggered relation with respect to those in the other series, and the several apertures being adjustable into registering relation as the gage key is moved longitudinally relative to the surface 15, so that when the gage key is so adjusted as to bring one of the apertures 25 into registry with an aperture in the gage plate, the parts may be locked together by a suitable locking means, shown herein to include clamping mechanism comprising a bolt 31 adapted to grip the tail portion 24, and an adjustable

threaded nut 32 adapted to be disposed on the outside of the gage plate 22 so as to be readily accessible to the operator.

In the use of my improved construction,

5 I have found that the various gages may be readily indicated upon the upper surface of the gage plate tail 26, the same being indicated, as shown in Fig. 6, by a series of parallel lines constituting projections of the axes 10 of the holes in the series 27, 28, 29, 30. Thus, when these lines are marked with the different gages, even an inexperienced or ignorant operator may very readily change the gage as desired by shifting the bolt 31 into 15 the registering holes corresponding to any given line. For instance, with the arrangement of holes shown in Figs. 5 and 6, a total variation in gage of one inch is obtained, in one-sixteenth inch changes, although obviously greater intermediate changes may be obtained by skipping any desired number of intermediate positions. It will also be evident that, as shown in Fig. 6, the largest gage 20 will be obtainable when the key 16 is at one limit of its travel, and that the smallest gage is obtainable when the key is at its opposite limit of travel, the intermediate gaging positions being located between these limits.

As a result of my improvement, it will 30 be noted that an exceedingly wide range of variation in gage is obtainable without the necessity for providing any loose parts which are adapted to become worn in service, the several elements constituting in effect a 35 unitary construction. It will also be observed that despite the variations in gage, the bit may be provided with the desired tapering working end, the angle of taper on the bit being maintained uniform regardless of the size of the bit and each bit having 40 that contour which provides reaming edges. Attention is also directed to the fact that the device is very conveniently located with respect to the swaging dies so that the 45 operator may readily correct the gage by simply transferring the bit to the gaging dies momentarily without the necessity for interrupting the operation of the swaging dies or the provision of any separate operating or controlling mechanism for the former. These and other advantages of my improved 50 construction will, however, be clearly apparent to those skilled in the art.

While I have in this application specifically described one embodiment which my invention may assume in practice, it is to be understood that the invention is not limited thereto but may be modified and embodied in various other forms without departing 55 from its spirit, it being my intention to include all such modifications within the scope of the appended claims.

What I claim as new and desire to secure by Letters Patent is:

60 1. Gaging die mechanism comprising a

plurality of dies including one die having a gaging groove therein of curved section and of flatter transverse curvature at one end than at the other.

2. Gaging die mechanism comprising a 70 plurality of dies, one of said dies being stationary and the other movable and having a gaging groove therein of curved section and of flatter transverse curvature at one end than at the other. 75

3. Gaging die mechanism comprising a plurality of dies including one having a gaging groove therein of curved section and of flatter transverse curvature at one end than at the other, and means cooperating with 80 said dies for locating a work piece at longitudinally different positions between said dies.

4. Gaging die mechanism comprising a 85 plurality of cooperating dies including a die having a transversely curved work engaging surface whose curvature varies from end to end of said surface and whose trace on a transverse plane is flatter at any point therealong than the arc of a circle of a diameter equal to the distance between the central point of said trace and the opposite point on the cooperating die. 90

5. Gaging die mechanism comprising a 95 plurality of dies, one of said dies being stationary and adapted to support a drill bit and the other die being movable and having a gaging groove therein of curved section and of flatter transverse curvature at one end than at the other and presenting a bit 100 engaging surface between its ends flatter at any point than an arc of a circle corresponding to the gage of a bit to be gaged at such point and resting on said stationary die. 105

6. In a forging machine, a stationary member, a member movable toward and away from said first mentioned member, and a gaging die member adjustably attached to one of said members and cooperating with the other thereof to gage and forge a piece of work. 110

7. In a forging machine, means for tapering the working end of a bit including adjustable die means for varying the gage of successive bits without varying the taper thereon. 115

8. In a forging machine, gaging members for tapering the working end of a bit including means for adjusting the working face of one of said members to vary the gage without varying the taper. 120

9. In a forging machine, stationary and movable swaging members each having a sloping surface thereon, and a gaging die adjustable longitudinally on one surface and cooperating with the other. 125

10. In a forging mechanism, a die support having a groove therein, a gaging die 130 slidable longitudinally in said groove and

- having an upper working face, and means for locking said die in a plurality of positions in said groove.
11. In a forging mechanism, a die support having a longitudinal groove therein, a gaging die slideable longitudinally in said groove and having an upper working face and an abutment thereon, and means for locking said die in a plurality of positions in said groove.
12. In a forging machine, stationary and movable members having inclined surfaces disposed at different angles, and a gaging die adjustable along the surface having the greater angle and having an upper working surface disposed at the same angle as the other surface.
13. In a forging mechanism, a die support having a groove therein provided with a sloping bottom, and a gaging die having an inclined surface slideable over the bottom of said groove, said die being provided with a working surface on its upper face and an abutment adjacent the same engageable with the cutting edge of a bit.
14. In a forging machine, a die support having an inclined groove therein, and a gaging die adjustable longitudinally of said groove and having a flat upper face provided with an inclined working surface adjacent one of its ends and an abutment adjacent one end of said working surface engageable with the cutting edge of a bit.
15. In a forging machine, swaging dies comprising stationary and movable members having cooperating sloping grooves therein and a gaging die adjustable longitudinally of one of said grooves and having a working surface cooperating with the bottom of the other groove, and means for locking said die to its member.
16. In a forging machine, stationary and movable members having inclined surfaces disposed at different angles to a line perpendicular to the line of movement of said movable member, a gaging die adjustable along the surface making the greater angle and having an outer working surface disposed at the same angle to said perpendicular line as the other surface but on the other side of said perpendicular line therefrom, whereby the total angle between said adjacent surfaces is double the angle of either to said perpendicular line and said total angle is bisected by the axis of a work piece between said surfaces, and means for locking said die in position.
17. In a forging machine, stationary and movable members having inclined surfaces disposed at different angles, and a gaging die adjustable along the surface having the greater angle and having a working surface disposed at the same angle as the other surface and a work engaging abutment adjacent said last mentioned surface.
18. In a forging machine, stationary and movable members having inclined surfaces disposed at different angles, a gaging die adjustable along the surface having the greater angle and having a working surface disposed at a smaller angle than the last mentioned surface, and means for locking said die in a plurality of positions with respect to said other surface.
19. In a forging machine, a die carrying member, a gaging die adjustable relative thereto, a gage plate fixed relative to said die carrying member, and means for locking said gaging die to said gage plate in any one of a plurality of positions.
20. In a forging machine, a die carrying member, a gaging die adjustable relative thereto, a gage plate fixed relative to said die carrying member, and means for locking said gaging die to said gage plate including registering apertures in the different elements.
21. In a forging machine, a member, a gage key member adjustable relative thereto, and means for locking the parts together including a series of apertures in one of said members and an aperture in the other member adapted to register successively with said apertures.
22. In a forging machine, a member, a gage key member adjustable relative thereto, and means for locking the parts together including a series of aligned apertures in one of said members and a plurality of series of aligned apertures on the other member.
23. In a forging machine, a member, a gage key member adjustable relative thereto, and means for locking the parts together including a series of apertures in one of said members and a plurality of series of apertures in the other adapted to register with said first mentioned apertures, the series on one member being disposed at an angle to a line parallel to the series of the other.
24. In a forging machine, a member, a gage key adjustable relative thereto, a gage plate fixed relative to said member, and means for locking said gage key to said gage plate in any one of a plurality of positions including an aperture in said key and a plurality of apertures in said plate adapted to register therewith.
25. In a forging machine, a member, a gage key adjustable relative thereto, a gage plate fixed relative to said member, and means for locking said gage key to said gage plate in any one of a plurality of positions including a plurality of apertures in said key and a plurality of apertures in said plate adapted to register therewith.
26. In a forging machine, a member, a gage key adjustable relative thereto, a gage plate fixed relative to said member, and means for locking said gage key to said gage plate.

plate in any one of a plurality of positions including a plurality of apertures in said key and a plurality of series of apertures in said plate adapted to register therewith.

5. 27. In a forging machine, a member, a gage key adjustable relative thereto, a gage plate fixed relative to said member, and means for locking said gage key to said gage plate in any one of a plurality of positions including a plurality of aligned apertures in said key and a plurality of series of aligned apertures in said plate adapted to register therewith.

10. 28. In a gaging mechanism, a supporting member, a gage key adjustable relative thereto and having an angularly extending portion provided with an aperture therein, a gage plate disposed parallel to said key and fixed to said support and having a projecting portion provided with a plurality of apertures therein, and locking means disposable through the registering apertures in said key and plate.

15. 29. In a forging machine, swaging dies comprising stationary and movable members having cooperating sloping grooves therein, a gage key adjustable longitudinally of one of said grooves and having a working surface cooperating with the bottom of the other groove, and means for locking said key to its die including a plurality of registering apertures and locking means disposable in said apertures.

20. 30. In a gaging mechanism, a supporting member, a gage key adjustable relative thereto and having an angularly extending portion provided with an aperture therein, a gage plate disposed parallel to said key and fixed to said support and having a projecting portion provided with a plurality of apertures therein, and locking means including a clamping bolt disposable through the registering apertures and a nut threaded on said bolt.

25. 31. In a forging machine, means for gaging a tapered bit comprising dies having work engaging surfaces formed at a less angle than the angle of the bits to be gaged thereby and adapted to engage the peripheral surface of the forward end of such a bit and change the angle of taper thereof.

32. In a forging machine, means for tapering the working end of a bit including adjustable rigid die means having opposed surfaces formed to such curvature as to vary 55 the gage of successive bits by swaging a terminal tapered portion of uniform length.

33. In a forging machine, a pair of swaging dies having opposed surfaces inclined in opposite directions at equal angles, one of 60 said dies being a key, and a support for said key, the engaging surfaces of said key and support being equally inclined and at a greater angle than the swaging surface of said key and cooperating with each other 65 to adjust said key.

34. In a forging machine, a die carrying member, a gaging die member adjustable relative thereto, and means for adjusting said members including an aperture in one 70 of said members and a plurality of apertures in the other adapted for registration therewith.

35. In a forging machine, stationary and movable members, one of said members having a groove therein whose bottom is disposed at an angle to the line of movement of said movable member, a gaging die 75 disposable in said groove, and means for locking said die in a plurality of positions in said groove.

36. In a forging machine, stationary and movable members, a gaging die member carried by one of said members and adjustable thereon in a line making an angle with the 85 line of movement of said movable member, and means for locking said die member in a plurality of adjusted positions on said die carrying member.

37. Gaging die mechanism comprising a 90 plurality of dies including a die having a gaging groove therein of curved section and of flatter transverse curvature at one end than at the other, and a cooperating die having a recess opposite to and adapted to co- 95 operate with said gaging groove during gaging of a work piece and having also an abutment adapted to be engaged by and to position a work piece.

In testimony whereof I affix my signature. 100

FRANK A. HALLECK.
